UNITED STATES PATENT OFFICE.

CHARLES ELLIOT WINSLOW, OF FORT ROBINSON, NEBRASKA.

DESIGN FOR A SPOON.

SPECIFICATION forming part of Design No. 22,562, dated June 27, 1893.

Application filed April 5, 1893. Serial No. 469,212. Term of patent 3½ years.

To all whom it may concern:

Be it known that I, CHARLES ELLIOT WINSLOW, a citizen of the United States, residing at Fort Robinson, in the county of Dawes 5 and State of Nebraska, have invented and produced a new and original Design for a Spoon; and I do hereby declare the following to be a full, clear, and exact description of the same, reference being had to the accompanying drawing, forming a part thereof.

The figure is a top plan view.

The drawing represents a spoon having my design which consists of a spoon or similar article having in the bowl thereof the representation of a mounted cavalry-man, the outline of which will be sufficiently small to admit of the representation of a landscape in the background, and having its handle formed

to represent a cavalry saber and scabbard. The scabbard forms the shank, the tip or drag 20 being at the point nearest the bowl and integral therewith and the handle of the saber, composed of the hilt, grip, pommel and guard forming the outer and wide end of the handle of the spoon. Suitably disposed around the 25 scabbard are representations of hanger rings.

What I claim is—

The design for a spoon substantially as herein shown and described.

In testimony whereof I affix my signature in 30 presence of two witnesses.

CHARLES ELLIOT WINSLOW.

Witnesses:

CHARLES R. SCHREIBER,
R. H. RUSSELL.
